WHIRLING TOY

Salvatore C. Parrilla, Cleveland, Ohio

Application July 13, 1959, Serial No. 56,761

Term of patent 14 years

(Cl. D34—15)

Fig. 1 is a top plan view of a whirling toy showing my new design;

Fig. 2 is an end elevational view taken from the lower end of Fig. 1;

Fig. 3 is a side elevational view taken from the right-hand side of Fig. 1;

Fig. 4 is a bottom plan view of the device; while

Fig. 5 is a side elevational view taken from the right-hand side of Fig. 4.

I claim:

The ornamental design for a whirling toy, as shown.
